(57) **CLAIM**

The ornamental design for a clinical solution blister pack carton portion, as shown and described.

DESCRIPTION

FIG. 1 is a perspective view of a clinical solution blister pack carton portion showing the new design;

FIG. 2 is a front elevation view thereof, the claimed portion of the rear elevation view being identical except for the unclaimed broken lines;

FIG. 3 is right side elevation view thereof, the left side elevation view being identical except for the unclaimed broken lines; and,

FIG. 4 is a bottom plan view thereof.

The portions of the blister pack carton portion shown in broken lines in the drawings form no part of the claimed design.
